UNITED STATES PATENT OFFICE

163,049

AIR CIRCULATOR UNIT

Jacob W. Kisling, St. Louis County, Mo.

Application October 21, 1949, Serial No. 5,617

Term of patent 14 years

(Cl. D26—7)

To all whom it may concern:

Be it known that I, Jacob W. Kisling, a citizen of the United States, residing in the county of St. Louis and State of Missouri, have invented a new, original, and ornamental Design for an Air Circulator Unit, of which the following is a specification, reference being had to the accompanying drawing, forming a part thereof.

In the drawing:

Fig. 1 is a top plan view of an air circulator unit, showing my new design;

Fig. 2 is a side elevational view thereof;

Fig. 3 is a top plan view of the stand portion shown in Fig. 1; and

Fig. 4 is a bottom plan view of the assembled air circulator. The opposite side of the air circulator of my design is the same as the side shown by Fig. 2.

The dotted lines in certain of the figures of drawing are for illustrative purposes only.

I claim:

The ornamental design for an air circulator unit, substantially as shown, and described.

JACOB W. KISLING.
